[57] CLAIM

I claim the ornamental design for a medical self-help table, as shown and described.

DESCRIPTION

FIG. 1 is an environmental perspective view of the medical self-help table as used by a reclined patient shown in phantom;

FIG. 2 is a rear elevational view thereof;

FIG. 3 is a front elevational view thereof;

FIG. 4 is a side elevational view, the opposite side being a mirror image thereof;

FIG. 5 is a top plan view thereof; and,

FIG. 6 is a bottom plan view thereof.

The broken lines in FIG. 1 are for illustrative purposes only and forms no part of the claimed design.
